WAITING CALL INDICATING DEVICE FOR
SEMAUTOMATIC TELEPHONE SYSTEMS

Eric Arvid Ericsson and Anton Christian Jacobus, Stockholm, Sweden, assignors to Telefonaktiebolaget L M Ericsson, Stockholm, Sweden, a company of Sweden

Application February 13, 1946, Serial No. 647,268
In Sweden March 15, 1945

4 Claims. (Cl. 179—27)

1

It often happens in telephone networks, that calls to certain subscriber's lines must be arranged in a queue. Special manual operating boards are arranged within local networks, to which the subscribers may apply when there arise difficulties to get through to a certain subscriber's number. On larger trunk exchanges there is an operating board for waiting calls, which takes care of all the trunk calls to subscriber's lines on which there is a queue. In such cases, calls to lines connected for waiting calls must be indicated in a special way, in order to avoid repeated resultless calls. It is known how to arrange that for trunk calls by means of a signal from the operating board for waiting calls to the line selector in the connection, over which the operating board for waiting calls is connected to the subscriber's line in question, said signal then producing such a change in the circuits over the helping wires of the subscriber's line, that calls to the subscriber's line are met by a special tone, indicating that the line is connected for waiting calls. This however requires devices both expensive and complicated.

The present invention intends to produce a simple and good solution of the above mentioned problem and achieves it, the calls being connected by means of registers, which are set according to the number of the subscriber's lines and are connectable, one at a time, to a control device common to all the registers, the connecting links pertaining to a manual operating board moreover being arranged for the connection of calls in a queue to subscriber's lines, said connecting links being provided with indicating devices which, in relation with the connection of a communication from the operating board for waiting calls, are set in accordance with the number of the called subscriber's line and are connected with said control device by means of circuits, over which it is controlled if the setting of a register, which is connected to the control device by a subscriber's establishing a communication, corresponds with the setting of one of said indicating devices, in which case the control device emits a signal to said register, either a special queue-indicating tone being sent to the caller, or the caller automatically being connected to the operating board for waiting calls.

The invention will be more closely described with reference to the accompanying drawings Figs. 1-3, which show an embodiment of the same for automatic trunk traffic. It is obvious, that the invention may as well be applied to au-

2

tomatic local traffic or to half automatic trunk traffic.

Fig. 1 shows the traffic paths within a trunk exchange I, which cooperates with a local exchange L. Trunk calls are dispatched over connecting links ISNR, which are connected to a register REG over a finder RS. After the register having been set, the trunk call is connected over the group-selector IGV1 to the group-selector GV2 of the local exchange and thereafter further to the called subscriber. If a queue has had to be arranged for the trunk calls to a subscriber's line, a communication is set up from a trunk operating board for waiting calls KB over a connecting link KSNR connected to the board and a group-selector KGV1 to said subscriber's line in the local exchange. A register REG thus takes part in the switching operation in a known way. At the same time as the register REG is set according to the subscriber's number, for instance by means of impulse trains, an indicating device M pertaining to the connecting link KSNR is also set in accordance with the subscriber's number.

25 There is a control device K common to all the registers REG and the indicating devices M, to which control device the registers REG can connect themselves one at a time, the indicating devices M, on the other hand, being connected to the control device over special indicating wires as soon as they have been set.

30 It may be arranged either so, that the registers REG, for each communication they establish, connect themselves to the control device K and examine if the called subscriber is connected to the operating board for waiting calls KB, or so that the line-selector of the local exchange can emit a signal to the register REG on the called line being busy, the register then connecting itself to the control device K and examining if the called subscriber is connected to the operating board for waiting calls.

35 If the register receives a signal from the control device K showing that the called subscriber is connected to the operating board for waiting calls, the circuits of the register are switched either so that the caller receives a special tone, or so that the caller is automatically connected to the operating board for waiting calls over the selectors IGV1 and TLV, a lamp then glowing at the connecting link KSNR in the operating board for waiting calls, the indicating device of which is set on the telephone number of the called subscriber. The operator in the operating board 40 for waiting calls is thus informed of the called

subscriber's number already before answering the call.

Fig. 2 and Fig. 3 show the circuits important for the invention in a 4-figures system arranged according to the principles mentioned in Fig. 1.

In each register REG there are four registering selectors Re1—Re4, each of which has an extra contact row, which is drawn in Fig. 2. There are likewise, in each of the indicating devices M, four registering selectors Re11—Re14, one for each figure of the 4-figures subscriber's numbers. There are 10 wires t_1 — t_{10} , one for each position corresponding to a figure in a registering selector Re1—Re4 or Re11—Re14, said wires being common to all the registers REG and the indicating devices M. Said wires are multiplicated to all the registers and indicating devices. On a communication having been set up over a connecting link KSNR in the operating board for waiting calls, relay RM7 attracts for the corresponding indicating device M, contacts 171—172 then being closed.

The common control device K is shown in Fig. 3 and contains a rotary selector V with three contact rows A—C and a stepping magnet VM. A relay chain may naturally replace said selector. The selector V is in position 1, when the control device is at rest, contact 1 then being broken and contact 2 closed.

When the switching operation in a register REG points out, that it has to control if the called subscriber is or is not connected to the operating board for waiting calls, a contact set G in Fig. 2 is actuated. The positive pole of the exchange battery is indicated by + in the following, and its negative pole by negative. On the drawings, the symbols + and — are being used. The following circuit is completed: +, contact set G, winding on relay RR1, discharge lamp GL, contact 21, wire e, contact strip B position 1 (Fig. 3), winding on relay GR1, contact 213, resistance r, to V—, which is the negative pole on a battery with a tension high enough to allow the discharge lamp GL to glow. The positive pole of said battery is connected to +. If the control device K is free, the discharge lamp KL glows, the voltage drop over resistance r then preventing other discharge lamps GL in other registers from glowing. If several registers attend to the control device K, only the discharge lamp, which has the lowest striking voltage, glows.

Relay RR1 attracts its armature. Contacts 11—17 are closed. Contact 15 short-circuits discharge lamp GL. Contacts 11—14 close the circuit from the selectors Re1—Re4 over wires a, b, c, d to the position in the control device K. Relay GR1 attracts its armature. Contacts 211—216 are actuated. Stepping magnet VM receives current over contacts 216 and 2 and selfbreaking contact 3 for VM. Selector V moves to position 2. Contacts 1—2 are actuated. The following circuit is completed, if the first figure of the called subscriber's number is registered on the selectors Re11 in one of the indicating devices M of the operating board for waiting calls: +, contact strip A position 2, winding on relay GR4, wire k1, contact 172, winding on relay RM1, selector Re11, one of wires t_1 — t_{10} , selector Re1, contact 11, wire a, contact strip B position 2 to negative. Relays RM1 and GR4 attract their armatures. Contacts 111—112 and 41—43 are actuated. Relays RM1 and GR4 are self held over contacts 112 and 41, resp., wire m and contact 215. Selector V continues to position 3.

If the first figure in the called subscriber's number is not registered on selector Re11 in one of the

indicating devices of the operating board for waiting calls, relay GR4 does not attract its armature. On selector V reaching position 3, the following circuit is completed: +, contact strip C position 3, contact 42, wire f, contact 16, winding on relay RR2 to negative. Relay RR2 attracts its armature and is self held over contact 22 and contact set G, and breaks the current for relays RR1 and GR1, which release their armatures. The register REG is thus freed from the control device K. It has thus been indicated in the register, that the called subscriber is not connected to the operating board for waiting calls. The control device K returns to position 1. If the selector V had been replaced by a relay chain, the replacement of the control device would have been effected immediately, which is important by large exchanges, especially when there is no busy signal from the line selector of the local exchange to the register REG and all the connections must apply to the control device.

In the following it is supposed, that relay GR4 and relay RM1 attract their armatures at least in one of the indicating devices M. On selector V reaching position 3, a new circuit is completed: +, contact strip A position 3, winding on relay GR5, wire k2, winding on relay RM2, contact 111, selector Re12, one of wires t_1 — t_{10} , selector Re2, contact 12, wire b, contact strip B position 3, to negative. Relay RM2 can now attract its armature among the indicating devices, in which relay RM1 has attracted its armature, if the setting of Re12 corresponds to the setting of Re2. Relay GR5 then also actuates. Contacts 121—122 and 51—52 are also actuated.

When selector V reaches the positions 4 and 5, what has been described above with regard to relays RM1 and RM2 together with GR4 and GR5 is now repeated for relays RM3 and RM4 together with relay GR6. No relay corresponding to GR4—GR6 in the control device is needed for the control circuit over position 5. If all the relays RM1—RM4 attract their armatures in one of the indicating devices, that means, that said indicating device is set on the same subscriber's number as the register REG connected to the control device. On relay RM4 attracting its armature contacts 141—142 are closed. The following circuit is completed: +, contact 141, winding on relay RM5, contact 162, wire h, winding on relay GR3, to negative. Relays RM4 and GR3 attract their armatures. Contacts 151, 231 and 232 are actuated.

On selector V reaching the position 6, relay GR2 attracts its armature due to the following circuit: +, contact 214, winding on relay GR2, contact strip B position 6, to negative. Contacts 221—222 are actuated. The selector V hereby remains in position 6.

If the setting of selectors Re4 and Re14 had not been the same, relays RM4, RM5 and GR3 would have attracted their armatures and the following circuit completed: +, contacts 232 and 221, wire f, contact 16, winding on relay RR2, to negative. Relay RR2 would then, as described above, have released the register REG and freed the control device, in which, after relays GR1 and GR2 having released their armatures, selector V continues to position 1.

It had been supposed, that relay GR3 had attracted its armature and contacts 231—232 been actuated. The following circuit is completed: +, contact 231, wire g, contact 17, winding on relay RR3 to negative. Relay RR3 attracts its armature and is self held over contact 31 and contact

set G. At the same time, relay RR3 actuates a number of contacts, which are not shown in the figure and which effect such a switching of the circuits of register REG, that the communication which is being connected over a group-selector IGV1 in Fig. 1 and a line selector TLV is connected to the operating board for waiting calls. Among the lines existing between the selectors TLV and the operating board for waiting calls, one only is pointed out, viz, the one which is indicated by contact 151 in Fig. 2. Selector TLV tests the winding on relay RM6, which attracts its armature and is self-held over contact 161. Contacts 161—166 are actuated. The lamp KL glows. The communication with the operator of the operating board for waiting calls is obtained over contacts 165 and 166. The circuits for relays RM1, RM4 and GR3 are broken and said relays release their armatures. Contact 232 is closed and relay RR2 in the register REG attracts its armature. Contact 21 breaks the circuit for relays RR1 and GR1, after which the register REG and the control device K are freed. Relays RM1—RM4 in the indicating device M release their armatures, but the selectors Rel1—Rel4 remain in their respective position.

The contact rows Rel1—Rel4 in the register REG may at the same time suit other purposes, such as indicating the setting of a register on a lamp-field common to all the registers and connected to the wires t_1 — t_{10} one figure at a time being indicated by means of special circuits. Such lamp-fields exist in the control desks in large automatic telephone exchanges.

We claim:

1. In an automatic telephone system arranged to permit queueing of calls to certain lines, a plurality of subscribers' lines, a plurality of registers each capable of being set to register the designation of a called subscriber's line, selectors for connecting an idle one of said registers to a calling subscriber's line upon initiation of a call thereover to conduct impulses corresponding to the designation of a called subscriber's line to said idle register to set the same, an operator's board, links connected to said board and to said selectors

5 to extend certain subscribers' lines to said board, an indicating device for each link and capable of being set to register the designation of said certain called subscriber's line, a control device common to all of said lines, said registers and said links, means for connecting said registers one at a time with said control device, indicating conductors common to all of said registers and said links, means in said control device connected to said indicating conductors for comparing the registration set in a register with the registrations set in said indicating devices, means under the control of the last-named means for emitting a signal to said register in response to correspondence of said registrations, and means in said register responsive to said signal for affording an indication to the calling subscriber.

10 2. The invention of claim 1, in which the means in said register responsive to said signal is arranged to disconnect the control device therefrom, and concurrently to connect a tone source to the calling subscriber's line.

15 3. The invention of claim 1, in which the means in said register responsive to said signal is arranged to disconnect the control device therefrom and concurrently to extend the calling subscriber's line to said operator's board.

20 4. The invention of claim 1, in which the means in said register responsive to said signal is arranged to extend the calling subscriber's line to that indicating device set to correspond to the registration in said register, and concurrently to disconnect said control device therefrom.

25 35 ERIC ARVID ERICSSON.
ANTON CHRISTIAN JACOBÆUS.
